 Benz, executor of said Herbert G. Benz, deceased

Application December 13, 1946, Serial No. 716,090

20 Claims. (Cl. 103—23)

1

My invention relates to an improvement in pumps and deals more particularly with a pump having radially movable pistons.

It is an object of the present invention to provide an effective pump capable of pumping liquid and the like. This pump involves radially movable pistons mounted for rotation about a common axis so that during rotation thereof each piston moves through one or more complete strokes.

A feature of the present invention resides in the manner in which the pistons are operated. Each piston is urged outwardly against an encircling casing by spring means and by centrifugal force. A wheeled carriage is provided for each piston, this carriage having wheels or rollers thereupon which engage against the encircling casing with a minimum of friction. The encircling casing has an eccentric inner surface which permits the pistons to travel inwardly and outwardly during each revolution thereof.

A feature of the present invention resides in the provision of radial cylinders having a passage from the inner extremity thereof into communication with fixed inlet and outlet ports. As the pistons move outwardly the communicating passage of the respective cylinder is in communication with a fixed inlet port. As the piston reaches its extreme outward position the communicating passage moves out of communication with the intake port and into communication with an outlet port. The communicating passage remains in communication with the outlet port during the inward stroke of the piston.

A feature of the present invention resides in the provision of a pump having radial pistons which are rotatable in a rotatable encircling casing. The casing has an eccentric inner surface to provide the radial movement of the pistons. When the pistons are rotating about a fixed center and the casing is held stationary, the pistons act to pump liquid or similar material. When the encircling casing is allowed to rotate with the pistons no pumping action takes place. A clutch means is provided for either holding the casing stationary or allowing the same to rotate. Similarly the clutch will allow the casing to rotate at a fraction of the speed of rotation of the pistons, thereby cutting down the pumping action.

A feature of the present invention resides in a novel and effective manner of holding the piston carriage rollers in place. Each roller is rotatable about a fixed axis having a pin projecting radially therefrom. Each roller is provided with a groove about its inner circumference in which the pin may slide. A notch is provided from one side of

2

the roller to the groove to permit the roller to be attached or detached from its axis.

These and other objects and novel features of my invention will be more clearly and fully set forth in the following specification and claims.

In the drawings forming a part of my specification:

- Figure 1 is a top plan view of my pump showing the construction thereof.
- 10 Figure 2 is a sectional view through the pump showing the construction thereof.
- Figure 3 is a sectional view at right angles to the axis of the pump, the position of the section being indicated by the line 3—3 of Figure 2.
- 15 Figure 4 is a sectional view through one of the piston carriages showing the manner in which the supporting rollers are connected thereto.
- Figure 5 is a sectional view through one of the piston carriage rollers, the position of the section being indicated by the line 5—5 of Figure 4.
- 20 Figure 6 is a sectional view through the pump near one end thereof, the position of the section being indicated by the line 6—6 of Figure 2.
- 25 Figure 7 is an elevational view of the central axis of the pump showing the intake and discharge ports therein.
- Figure 8 is an end view of the central axis illustrated in Figure 7.
- 30 The pump A includes an outer casing having a substantially cylindrical outer shell 10 provided with a closed end 11 thereupon. Within the outer shell 10 I provide an inner casing which includes a hollow cylindrical sleeve 12 having proper outer diameter to snugly fit within the shell 10. The sleeve 12 has at one end thereof an end closure 13 comprising a relatively thick ring shaped body having a wide peripheral groove 14 extending thereabout. The inner sleeve 12 is likewise provided with a peripheral flange 15 which engages snugly within an internal groove 16 at the end of the outer casing 10.
- 35 The end closure 13 has an axial aperture 17 therethrough which serves as a bearing for the enlarged diameter portion 19 of the drive shaft 20. The enlarged diameter portion 19 of the drive shaft is provided with a series of radially extending rectangular projections 21 in which the radial pump cylinders are provided. Each projection 21 includes a radially extending bore 22 for accommodating a thimble shaped piston 23. A spring 24 is interposed between the closed end of the piston which is the farthest end from the axis of rotation thereof and the base of the cylinder 22.
- 40 The enlarged diameter portion 19 of the shaft

20 is hollow to accommodate the central axis member 25. A passage 26 extends through the wall of this hollow enlarged shaft portion 19 communicating with each cylinder or bore 22. The liquid drawn into the cylinder by the piston is drawn through this communicating passage 26. Likewise the liquid pumped by each piston 23 is forced in a reverse direction through the passage 26, as will be later described in detail.

A hollow box like enclosure is slidably supported on each rectangular projection 21. Each enclosure 27 has a rectangular axial aperture 29 therein. The enclosures 27 are also provided as illustrated in Figure 4 of the drawings with a pair of stub shafts 30 and 31 extending from opposite sides thereof. Rollers 32 and 33 are rotatably supported on the stub shafts 30 and 31 respectively. The rollers 32 and 33 are designed to engage against the eccentric inner surface of the enclosing casing so as to move the pistons in a radial direction with a minimum of friction.

A pin 34 is mounted in the stub shaft 30 to extend radially therefrom. This pin 34 is engageable in a circular groove 35 extending about the inner circumference of the roller 32. A notch 36 is provided extending in an axial direction from the inner edge of the roller 32 to the groove 35.

In mounting the roller 32 upon the stub shaft 30, the notch 36 is aligned with the pin 34 and the roller moved axially until the pin 34 is in registry with the groove 35. The roller may then rotate freely and is held in place by the pin 34.

The roller 33 is similarly held in place by a pin 38 projecting radially from the stub shaft 31. This pin 38 engages in a circular groove 37 in the inner circumference of the roller 33. A communicating groove 39 extends from the inner edge of the roller into communication with the groove 37. The roller 33 is inserted in place by placing the notch 39 in registry with the pin 38 and moving the roller axially until the pin 38 is in registry with the groove 37, whereupon the roller may rotate freely.

As will be noted in Figure 4 of the drawings passages 40 extend through the side walls of the enclosure 27 and apertures 41 extend through the end wall 42 thereof. Air or oil may flow through these apertures so as to equalize pressure inside and outside of the enclosure 27 during movement thereof.

It will be noted that the rollers 32 and 33 project slightly beyond the end wall 42 of the enclosure 27. As a result the rollers engage against the inner wall of the enclosure and permit the enclosure to move in a radial direction on the projections 21 with a minimum of friction.

The rotor casing 43 includes a sleeve 44 having a cylindrical outer surface and an oval inner surface, as best illustrated in Figure 3 of the drawings. The oval inner surface is shown as being relatively thick at diametrically opposed points 45 and as having a relatively thin wall at diametrically opposed points 46 ninety degrees from the points 45. As a result the piston carriages or enclosures 27 are allowed to move outwardly and inwardly a distance equal to the difference in thickness of the casing wall at the points 45 and 46 twice during each revolution of the pistons relative to the casing. The casing 43 is provided with an end closure 47 integral with one end of the sleeve 44. Angularly spaced apertures 49 are provided in the cylindrical sleeve portion 44 and similar angularly spaced apertures 50 are provided in the end closure 47 to permit oil to flow freely on opposite sides of the end closure and

also to flow between the sleeve portion 44 and the enclosing sleeve 12. It will be noted that the enclosure 43 is provided with two larger diameter circumferential rings 51 and 52 which snugly engage within the sleeve 12. The sleeve 43 between these rings 51 and 52 is slightly spaced from the sleeve 12 to permit a flow of oil between the two sleeves.

An end washer 53 is interposed between the free end of the sleeve portion 44 and the end closure 47 on the sleeve 12. This washer 53 is provided with a series of angularly spaced apertures 54 therethrough which may rotate into communication with any of a series of angularly spaced apertures 55 leading to the peripheral groove 14.

The washer 53 is provided with opposed ears 56 which engage in notches 57 in the free end of the sleeve portion 44 of the rotor casing 43. These ears 56 cause the washer 53 to rotate in unison with the casing 43. A bearing sleeve 59 extends through an axial aperture 69 in the end closure plate 47 of the casing 43 and is designed to rotate with this casing. A collar 61 is secured to the bearing sleeve 59 to rotate therewith and with the casing 43. This collar 61 is provided with external spline teeth 62 and internal spline teeth 63. A collar 64 connects the collar 61 with the central distributor element or central axis 25. The collar 64 is provided with external spline teeth which engage between internal spline teeth 63 of the collar 61. This collar 64 is also provided with internal spline teeth 66 which engage between external teeth 70 on the circumference of the axis or distributor element 25. An internal flange 67 on the collar 64 holds the distributor element 25 in proper position within the casing 43. The external teeth 70 on the distributor element 25 may be best seen in Figure 7 of the drawings, which shows this element in detail.

The distributor element 25 has as its primary purpose the function of providing fluid to the cylinders during the intake stroke of the various pistons and the delivery of fluid under pressure from the cylinders during the power strokes of the piston. To serve this purpose the distributor element 25 is provided with a large diameter portion 71 which fits snugly within an axial bore 72 within the large diameter portion 17 of the drive shaft 20. The distributor portion 71 is provided with four peripheral grooves therein which are angularly spaced apart. Two opposed grooves 73 and 74 are connected by an aperture 75 through the large diameter portion 71, thus connecting both of the grooves 73 and 74 with an axial passage 76 which extends through the distributor member 25 to the small diameter end thereof. The axial passage 76 does not extend through the large diameter end 71 of the element 25 for a purpose which will be later described in detail.

The remaining opposed slots 77 and 79 are connected by longitudinally extending grooves 80 and 81, respectively, to the end of the element 25. The various slots are angularly spaced apart a distance equal or slightly larger than the diameter of the apertures 26 leading through the shaft portion 19 into communication with the cylinders 22. Thus during the rotation of the drive shaft each radial passage 26 is moved first into communication with one of the grooves 73 or 74, and next into communication with one of the grooves 77 or 79 and between times is closed.

The end 82 of the element 25 is externally threaded to receive a bearing cap 83 having an axial aperture 84 therethrough to communicate

with the aperture 76 in the element 25. A gasket 85 is interposed between the bearing cap and the end of the element 25 so as to form a seal between these elements. A peripheral flange 86 is provided on the bearing cap 83 to limit end-wise movement of the bearing cap. A seal 87 is interposed between the flange 86 and the closure end 11 so as to prevent the escape of fluid about the bearing 83. The bearing cap 83 is provided with a slot 89 in the extremity thereof by means of which the sleeve may be disengaged from the element 25.

The end plate 11 of the casing 10 is provided with a central boss 90 which is internally threaded to accommodate the reducer 91. The reducer 91 includes an externally threaded sleeve 92 having an end 93 thereupon equipped with an axial internally threaded aperture 94 for accommodation of a nipple or fitting 95. The nipple or fitting 95 may be connected to any pressure line to supply fluid under pressure thereto.

The end plate 11 of the casing 10 is also provided with a boss 96 off-set from the center thereof. An elongated sleeve 97 extends through an aperture 99 in the boss 96. The sleeve 97 is provided with a shoulder 100 to limit the insertion of the sleeve 97. This sleeve is provided with a hexagonal portion 101 at one end thereof, by means of which the sleeve may be rotated. A shaft 102 extends through the sleeve 97 and is provided with a pinion 103 on its inner extremity within the casing 10. A nut 104 is threaded on the end of the shaft 102 to hold the pinion 103 in place. A set screw 105 may be provided to connect the sleeve 97 to the shaft 102 to cause rotation thereof in unison.

The pinion 103 engages the internal teeth of a ring rear 106 formed on the inner extremity of the flange 107 on the end of an externally threaded sleeve 109. This sleeve 109 is provided with spline teeth 110 on its internal surface and the external threads thereupon cooperate with internal threads on the free end of the sleeve 12.

A series of clutch discs are interposed between the flange 107 of the threaded sleeve 109 and the closed end 47 of the casing 43. These discs provide a clutch between the elements described. Alternate discs 111 are spline connected to the sleeve 109. The intermediate discs 112 are spline connected to the external surface of the collar 61. By moving the flanged end 107 of the sleeve 109 toward the casing end 47, axial pressure is exerted against the discs which tends to either hold the casing 43 stationary with respect to the outer pump casing or allow free rotation of the casing 43. The axial pressure is provided by rotating the threaded sleeve 109 in a direction to thread this sleeve into the internally threaded sleeve 12. Axial pressure against the clutch discs is relieved by rotating the threaded sleeve 109 in the opposite direction. Rotation of the sleeve 109 is effected by rotating the pinion 103 with the shaft 102.

An axial recess 113 is provided in the end closure 13 to accommodate an oil seal 114. This oil seal 114 prevents the flow of the fluid between the shaft 20 and the end 13 of the casing. The seal 114 is held in place by an externally threaded plug 115 which engages into the internal threads of the aperture 113.

It will be noted that a series of angularly spaced apertures 116 are provided through the end of the large diameter portion 19 of the drive shaft 20 so as to permit oil to flow into the interior of the hollow shaft portion 19. The passages 116

communicate with an annular chamber 117 externally of the shaft 20 and inwardly of the oil seal 114. The chamber 117 is in communication with the peripheral groove 14 through a series of angularly spaced passages 119. An oil inlet 120 is provided on the outer casing sleeve 10 in communication with the peripheral groove 114. As the pump is usually used to pump oil or similar material which also may be used as a lubricant, the oil intake is connected to the interior of the pump so that the incoming oil may lubricate the parts thereof.

Key ways are provided between the end closure 13 and the casing 10 to prevent relative rotation between these parts. The pump illustrated is designed for attachment against a drive mechanism and accordingly is provided with an end flange 121 having angularly spaced apertures 122 therethrough by means of which the pump may be attached to the drive device. If the pump is to be driven from a distant power supply, means must be provided for connecting the end closure 13 with the casing 10 to prevent separation of these elements.

The operation of my pump is believed obvious from the foregoing description. Oil enters through the inlet 120, and is drawn into the peripheral groove 14 in the end closure 13 of the casing. From the peripheral groove 14 oil may flow through the passages 119 into the interior of the rotatable casing 43. This casing is provided with openings therethrough so that the exterior surface thereof is lubricated during operation of the pump. The enclosures 27 are also lubricated so as to slide readily upon the projections 21. The rollers 32 and 33 on the enclosures 27 are also properly lubricated by this means.

Oil entering the pump may flow through the passages 119, the chamber 117, and the passages 116 to the interior of the hollow portion 19 of the drive shaft 20. Oil entering this shaft portion may be communicated with the inlet slots 71 and 79 through the longitudinally extending grooves 80 and 81. During the outward or suction stroke of the pistons the passage 26 associated therewith is in communication with one of these inlet grooves.

When the piston has reached the outward limit of its stroke the respective passage 26 passes out of communication with the inlet ports 71 or 79 and passes into communication with one of the outlet port grooves 73 or 74. During the inward stroke of each piston, oil is forced inwardly through the passage 26 and into the outlet port groove 73 or 74 through which oil is forced into the axial passage 76 and thus outwardly through the connecting nipple 75.

The collar 64 provides a timing means for adjusting the position of the distributing element 25 relative to the casing 43. Obviously the element 25 must be in proper time with the casing 43 so that the oil is drawn from the inlet ports during the outward stroke of the pistons and forced into the outlet ports on the power stroke of each piston. With the arrangement illustrated in Figure 3 of the drawings the pistons are arranged to rotate in a clockwise direction relative to the casing in order to operate as described. In the event it was desired to rotate the pistons in the opposite direction relative to the casing, the distributing element 25 would have to be rotated through an angular distance of ninety degrees to properly time the pump.

When the pump is started in operation, if the axial pressure upon the clutch plates 111 and

112 is relieved, the casing 43 will rotate in unison with the drive shaft. As a result the pistons will not move radially in their cylinders and no oil will be pumped. By rotating the shaft 102 and the pinion 103 the threaded sleeve 109 may be threaded into the casing sleeve 12. As a result axial pressure is exerted against the clutch discs 111 and 112 causing friction therebetween. As friction is provided between the clutch plates the speed of rotation of the casing 43 decreases to a point where when the clutch is tight the casing 43 is held from rotation. When the casing 43 is held stationary the pistons will operate at their greatest speed and the maximum pumping action will be effected.

It will be seen that I have provided a pump which may be rotated constantly with a minimum of friction and power loss, particularly when the inner casing is allowed to rotate. When the clutch is free the inner casing will rotate and no pumping action will be provided. By merely tightening the clutch any desired proportion of the total pumping capacity of the pump may be provided by registering the amount of slippage between the inner casing and the drive shaft.

When the cylinders are rotating relative to their casing the pistons are operating with a minimum of friction because of the rollers which bear against the inner surface of the oval casing. Obviously the enclosures 27 may freely fit the projections 21 upon which they slide, and it is only necessary to provide a close fit between each piston and its cylinder in order to provide an efficient pumping operation.

In accordance with the patent statutes, I have described the principles of construction and operation of my pump, and while I have endeavored to set forth the best embodiment thereof, I desire to have it understood that this is only illustrative thereof, and that obvious changes may be made within the scope of the following claims without departing from the spirit of my invention.

I claim:

1. A pump including a series of radially extending cylinders, means supporting said cylinders rotatable about a central axis, pistons in said cylinders, a casing within which said cylinders are rotatably supported, an inner non-circular surface on said casing and engaging said pistons for moving said pistons radially in their cylinders, means for rotatably supporting said casing, and means engageable with said casing for holding the same from rotation.

2. A pump including a drive shaft, a series of radially extending cylinders secured to said drive shaft for rotation therewith, pistons supported in said cylinders for radial movement with respect to said drive shaft, a casing within which said cylinders rotate, said casing having a non-circular inner surface engaging said pistons and operating to reciprocate said pistons when said drive shaft rotates relative to said casing, means rotatably supporting said casing, and means engageable with said casing for holding the same from rotation.

3. A pump including a drive shaft, a series of radially extending cylinders secured to said drive shaft for rotation therewith, pistons supported in said cylinders for radial movement with respect to said drive shaft, a casing within which said cylinders rotate, said casing having an inner non-circular surface, means on said pistons engaging said surface and operating to recipro-

cate said pistons when said drive shaft rotates relative to said casing, and means rotatably supporting said casing, clutch means engageable with said casing to selectively hold said casing from rotation or permit said casing to rotate with said drive shaft.

4. A pump including a drive shaft, a series of radially extending cylinders secured to said drive shaft for rotation therewith, pistons supported in said cylinders for radial movement with respect to said drive shaft, a casing within which said cylinders rotate, said casing having an inner non-circular surface, means on said pistons engaging said surface and operating to reciprocate said pistons when said drive shaft rotates relative to said casing, means rotatably supporting said casing, means engageable with said casing to hold the same from rotation, a communicating passage from each cylinder through which fluid may flow in either direction, and inlet and outlet ports with which each said passage is alternately engaged in the rotation of said drive shaft.

5. A pump including a drive shaft, a series of radially extending cylinders secured to said drive shaft for rotation therewith, pistons supported in said cylinders for radial movement with respect to said drive shaft, a casing within which said cylinders rotate, said casing having an inner non-circular surface, means on said pistons engaging said surface and operating to reciprocate said pistons when said drive shaft rotates relative to said casing, means rotatably supporting said casing, means engageable with said casing to hold the same from rotation, a communicating passage from each cylinder through which fluid may flow in either direction, and inlet and outlet ports with which each said passage is alternately engaged in the rotation of said drive shaft relative to said casing.

6. A pump including a drive shaft, a series of radially extending cylinders secured to said drive shaft for rotation therewith, pistons supported in said cylinders for radial movement with respect to said drive shaft, a casing within which said cylinders rotate, said casing having an inner non-circular surface, means on said pistons engaging said surface and operating to reciprocate said pistons when said drive shaft rotates relative to said casing, means rotatably supporting said casing, means engageable with said casing to hold the same from rotation, a passage in said drive shaft in communication with each of said cylinders, and distributor means connected to said casing, said distributor means including inlet and outlet ports with which said passages are alternately connected in the rotation of said drive shaft relative to said casing.

7. A pump including a drive shaft, a series of radially extending cylinders secured to said drive shaft for rotation therewith, pistons supported in said cylinders for radial movement with respect to said drive shaft, a casing within which said cylinders rotate, said casing having an inner non-circular surface, means on said pistons engaging said surface and operating to reciprocate said pistons when said drive shaft rotates relative to said casing, means rotatably supporting said casing, means engageable with said casing to hold the same from rotation, said casing allowing said pistons to move outwardly to provide an intake stroke and inwardly to provide a power stroke, a passage from each cylinder in said drive shaft through which fluid may enter and leave the cylinder, and a distributor con-

nected to said casing for rotation therewith, said distributor connecting each passage with an inlet port during the intake stroke of each piston and connecting each passage with an outlet port during each power stroke.

8. A pump including a drive shaft, a series of radially extending cylinders secured to said drive shaft for rotation therewith, pistons supported in said cylinders for radial movement with respect to said drive shaft, a casing within which said cylinders rotate, said casing having an inner non-circular surface, means on said pistons engaging said surface and operating to reciprocate said pistons when said drive shaft rotates relative to said casing, means rotatably supporting said casing, means engageable with said casing to hold the same from rotation, an axial aperture within said drive shaft, passages extending from the base of each cylinder to the interior of said drive shaft, and a distributor within said drive shaft, said distributor including inlet and outlet ports which are alternately connected to each said passage during rotation of said drive shaft relative to said casing.

9. A pump including a drive shaft, a series of radially extending cylinders secured to said drive shaft for rotation therewith, pistons supported in said cylinders for radial movement with respect to said drive shaft, a casing within which said cylinders rotate, said casing having an inner non-circular surface operating to reciprocate said pistons when said drive shaft rotates relative to said casing, means rotatably supporting said casing, means engageable with said casing to hold the same from rotation, an axial recess in said drive shaft, a distributor element in said recess, said distributor element comprising an elongated shaft about which said drive shaft may rotate, said elongated shaft having grooves in the surface thereof, alternate of which are connected by passages to one end of the elongated shaft, and the remainder of which are connected by passages to the other end of said elongated shaft, and passages through said drive shaft from each cylinder to the interior of the drive shaft, said passages being alternately communicable with said grooves upon rotation of said drive shaft.

10. A pump including a drive shaft, a series of radially extending cylinders secured to said drive shaft for rotation therewith, pistons supported in said cylinders for radial movement with respect to said drive shaft, a casing within which said cylinders rotate, said casing having an inner non-circular surface operating to reciprocate said pistons when said drive shaft rotates relative to said casing, means rotatably supporting said casing, means engageable with said casing to hold the same from rotation, a carriage slidably supported for radial movement upon each of said cylinders, said carriage engaging the inner surface of said casing and engaging the outer extremity of a corresponding piston.

11. A pump including a drive shaft, a series of radially extending cylinders secured to said drive shaft for rotation therewith, pistons supported in said cylinders for radial movement with respect to said drive shaft, a casing within which said cylinders rotate, said casing having an inner non-circular surface operating to reciprocate said pistons when said drive shaft rotates relative to said casing, means rotatably supporting said casing, means engageable with said casing to hold the same from rotation, a radially reciprocable carriage slidably supported on each of

said radial cylinders, said carriage extending between one end of each piston and the inner surface of said casing, and apertures through said carriage to equalize pressure on opposite sides thereof.

12. A pump including a drive shaft, a series of radially extending cylinders secured to said drive shaft for rotation therewith, pistons supported in said cylinders for radial movement with respect to said drive shaft, a casing within which said cylinders rotate, said casing having an inner non-circular surface operating to reciprocate said pistons when said drive shaft rotates relative to said casing, means rotatably supporting said casing, means engageable with said casing to hold the same from rotation, an enclosing element slidably supported on each of said cylinders for radial reciprocation thereon, and roller means on said enclosure engageable against the inner surface of said casing.

13. A pump including a drive shaft, a series of radially extending cylinders secured to said drive shaft for rotation therewith, pistons supported in said cylinders for radial movement with respect to said drive shaft, a casing within which said cylinders rotate, said casing having an inner non-circular surface operating to reciprocate said pistons when said drive shaft rotates relative to said casing, means rotatably supporting said casing, means engageable with said casing to hold the same from rotation, a radially reciprocable cap slidably supported on each radial cylinder, the base of each cap extending between the outer end of one of said pistons and the inner surface of said outer casing.

14. A pump including a drive shaft, a series of radially extending cylinders secured to said drive shaft for rotation therewith, pistons supported in said cylinders for radial movement with respect to said drive shaft, a casing within which said cylinders rotate, said casing having an inner non-circular surface operating to reciprocate said pistons when said drive shaft rotates relative to said casing, means rotatably supporting said casing, means engageable with said casing to hold the same from rotation, means slidably supported upon each of said radially extending cylinders for radial reciprocation thereon, said last named means engaging the piston within said cylinder to reciprocate the same, and roller means on said last named means engageable with the inner eccentric surface of said casing.

15. A pump including a drive shaft, a series of radially extending cylinders secured to said drive shaft for rotation therewith, pistons supported in said cylinders for radial movement with respect to said drive shaft, a casing within which said cylinders rotate, said casing having an inner non-circular surface operating to reciprocate said pistons when said drive shaft rotates relative to said casing, means rotatably supporting said casing, means engageable with said casing to hold the same from rotation, a piston actuating means radially slidably supported by each of said radial cylinders, said piston actuating means engaging the inner end of a corresponding piston to reciprocate the piston in unison therewith, and a pair of opposed rollers supported by said piston actuating means on an axis parallel to the axis of said drive shaft engageable against the inner surface of said casing.

16. A pump including a drive shaft, a series of radially extending cylinders secured to said drive shaft for rotation therewith, pistons supported

in said cylinders for radial movement with respect to said drive shaft, a casing within which said cylinders rotate, said casing having an inner non-circular surface operating to reciprocate said pistons when said drive shaft rotates relative to said casing, means rotatably supporting said casing, means engageable with said casing to hold the same from rotation, a piston actuating means radially slidably supported by each of said cylinders for engaging a corresponding piston to reciprocate the same, a pair of stub shafts on said piston actuating means extending substantially parallel to said drive shaft, a pin extending radially from each said stub shaft, and a roller rotatably supported on each stub shaft and including an internal circumferential groove for accommodating said pin, and an axially extending groove communicating with said first named groove.

17. A pump including a drive shaft, a series of radially extending cylinders secured to said drive shaft for rotation therewith, pistons supported in said cylinders for radial movement with respect to said drive shaft, a casing within which said cylinders rotate, said casing having an inner non-circular surface operating to reciprocate said pistons when said drive shaft rotates relative to said casing, means rotatably supporting said casing, means engageable with said casing to hold the same from rotation, roller supporting means for connecting a roller to a stub shaft comprising a pin projecting from said stub shaft in a generally radial direction, a roller having an aperture therethrough of a size to slidably engage the surface of the stub shaft, a circular groove between the ends of said roller communicating with the aperture through the roller, said groove being of a size to freely accommodate said pin, and an axial groove connecting said circular groove with one end of said roller through which said pin may pass in inserting said roller onto said shaft.

18. A pump comprising an outer casing, an inner casing within said outer casing, an inner non-circular surface on said inner casing, a drive shaft extending into said outer casing, a series of radially extending projections connected to said drive shaft for rotation therewith, a radially extending cylinder in each of said projections, a piston in each said cylinder, each said piston being radially slidable and actuated in a radial direction by the inner surface of said inner casing, an inlet and outlet passage to each said cylinder, a series of clutch discs adjacent said casing, alternate of said clutch discs being secured to said casing for rotation therewith and the remaining discs being relatively fixed, and means for applying axial pressure against said discs to cause frictional engagement therewith.

19. A pump comprising an outer casing, an inner casing within said outer casing, an inner non-circular surface on said inner casing, a drive shaft extending into said outer casing, a series of radially extending projections connected to said drive shaft for rotation therewith, a radially extending cylinder in each of said projections, a piston in each said cylinder, each said piston being radially slidable and actuated in a radial direction by the inner surface of said inner casing, an inlet and outlet passage to each said cylinder, a series of clutch discs adjacent said casing, alternate of said clutch discs being secured to said casing for rotation therewith and the remaining discs being relatively fixed, and means for applying axial pressure against said discs to cause frictional engagement therewith, said means comprising a collar threadably engaged to said outer casing and engageable against said discs to exert a compressive action thereupon.

20. A pump comprising an outer casing, an inner casing within said outer casing, an inner non-circular surface on said inner casing, a drive shaft extending into said outer casing, a series of radially extending projections connected to said drive shaft for rotation therewith, a radially extending cylinder in each of said projections, a piston in each said cylinder, each said piston being radially slidable and actuated in a radial direction by the inner surface of said inner casing, an inlet and outlet passage to each said cylinder, a series of clutch discs adjacent said casing, alternate of said clutch discs being secured to said casing for rotation therewith and the remaining discs being relatively fixed, and means for applying axial pressure against said discs to cause frictional engagement therewith, said means comprising a collar threadably engaged to said outer casing and engageable against said discs to exert a compressive action thereupon, and means for rotating said collar including a ring gear connected to said collar and a pinion rotatably supported by said casing, and means for rotating said pinion to rotate said collar.

FRITZ STEPHAN.
